UNITED STATES PATENT OFFICE

2,668,545

POCKET CIGARETTE-MAKING DEVICE

George Burnstein, Norristown, Pa.

Application October 10, 1949, Serial No. 120,430

7 Claims. (Cl. 131—70)

1

The present invention relates generally to cigarette-making devices adapted to be conveniently carried in the pocket, and more particularly to a simple, efficient and compact device for facilitating the making of cigarettes from preformed cigarette tubular papers and appropriately-cut tobacco, the device being generally in the form of a hinged-cover case which is operable upon closure of the cover to securely position and adequately support a cigarette paper in properly disposed relation to a tobacco filling tube during the step of tamping the tobacco into the paper tube or wrapper for the cigarette.

Among the principal objects of the present invention is the provision of a cigarette making device in the form of a compact casing having at one end thereof a compartment from whence tobacco may be forced into the cigarette tube or wrapper which is securely held, as above-mentioned, within the interior of the closed casing, the end compartment being provided with a short cigarette filling tube extending interiorly of the casing and which serves not only to direct the tobacco into the cigarette paper, but also to maintain the mouth of the paper suitably expanded to facilitate proper filling of the paper with tobacco.

Still another object of the invention is to provide means arranged internally of the casing and operable upon closure of its cover to hold the cigarette paper axially aligned with the filling tube for proper filling thereof with tobacco, said means being further operative to close or seal the outer end of the cigarette paper during the operation of charging it with tobacco.

With these and other objects in view, it will be understood that the present invention resides in the novel construction, combination, location and arrangement of parts more fully described and pointed out in the following specification and claims, and illustrated in the accompanying drawings, of which—

Figure 1 is a perspective view of the cigarette forming device of the present invention showing the same with its cover in closed position;

Figure 2 is a front elevational view of the device with the cover in opened position;

Figure 3 is a vertical cross-sectional view of the device as taken on line 3—3 of Figure 2 with the cover in closed position;

Figure 4 is a horizontal cross-sectional view of the device as taken on line 4—4 of Figure 3;

Figure 5 is a horizontal cross-sectional view of the device as taken on line 5—5 of Figure 3;

Figure 6 is a front elevational view, similar to

2

Figure 2, showing a modified form of the present invention;

Figure 7 is a vertical cross-sectional view of the modification as taken on line 7—7 of Figure 6 with the cover in closed position; and

Figure 8 is a horizontal cross-sectional view of the modification as taken on lines 8—8 of Figure 7.

Referring now to the drawings and more particularly to Figures 1 to 5 thereof, it will be observed that in one form of the cigarette making device as constructed in accordance with the present invention it comprises a pocket-size box-like member or casing 10 having a tobacco-receiving compartment 11 at one end thereof, said compartment being separated from the interior of the casing by a bottom wall 12 which is substantially co-planar with the upper edge of a closure 13 suitably hinged to a vertical edge of the casing, as at 13', this closure being readily opened, as in Figure 2, to provide access to the interior of the casing. The compartment 11 is fitted in its bottom wall with a short open-ended tube 14 extending vertically downwardly into the interior of the casing 10, the freely projecting end of said tube 14 being adapted to have slipped thereon one end of a tubular cigarette paper wrapper 15, as shown in Figures 2 and 3. A plunger 16, of a diameter only slightly less than that of the tobacco filling tube or nozzle 14, is employed to push tobacco from compartment 11 through the tube 14 into the paper wrapper 15 to form a cigarette. The plunger 16 being preferably of a length which enables it to be projected through the filler tube 14 into the casing 10 for retention therein when the device is not in use.

In the process of forming a cigarette, one end of the tubular cigarette paper 15 is first slipped over the projecting end of the tobacco filling tube 14, the paper being then securely clamped to the tube by an arcuately shaped resilient pad 17 so mounted upon the inner face of the closure 13 that when the latter is swung into closed position (as shown in Figures 3 and 4), when the case is closed said pad cooperates with tube 14 to clampingly engage the cigarette paper therebetween. The clamping member 17, preferably comprising a block of resilient rubber, is formed with a clamping surface of generally semi-circular shape, said clamping surface being in such conformity with the cylindrical surface of the tube 14 as to clampingly embrace therebetween the cigarette paper for approximately half of its circumference.

It is, of course, desirable to support the main

body portion of the cigarette paper 15 adequately during the tobacco tamping and cigarette forming process, and to this end, in one modification of the present invention, coacting means are provided in the form of a trough-shaped member 18 fixedly mounted by a pair of vertically spaced elements 18-18' interiorly of the casing 10 so as to be in co-axial relation with the tube 14 and a resilient clamping pad 19, preferably formed of soft rubber, secured to the inner face of the closure 13 for overlying engagement with the open portion of the member 18, the clamping face of the pad 19 being shaped to provide a longitudinally extending groove 20 of a shape adapting it to snugly embrace the outer portion of the cigarette nested in the trough-shaped member 18. When the closure member 13 is swung into its closed position, as shown in Figures 3 and 5, the longitudinally grooved resilient pad 19 and the trough-shaped member 18 conjointly provide an elongated recess for reception of the cigarette paper extending from the tobacco filling tube 14, this recess being in such axial alignment with said tube 14 as to insure adequate support of the cigarette paper upon rectilinear projection of the plunger 16 into the paper during the tobacco filling operation.

The closure 13 of the casing 11 may be held in closed position by suitable coacting catch elements 21-22, while the interior of the casing 30 may be fitted with clip members 23-23 for the support therein of cigarette papers and completed cigarettes.

In the arrangement of the device as shown in Figures 1 to 5, it will be observed that the lower end of the trough-shaped member 18 is provided with a bottom wall member 24 extending transversely of the cigarette axis, this member being adapted to serve as a closure for the abutting extremity of the tubular cigarette paper 15. Thus, as the plunger 16 is actuated to tamp tobacco from the compartment 12 into the cigarette paper, the bottom wall member 24 prevents escape of the tobacco from the lower end of the cigarette paper.

In the modified arrangement of the device as shown in Figures 6 to 8, inclusive, the lower end of the cigarette paper is closed against escape of tobacco therefrom by a pair of resilient clamp members 25 and 26 respectively mounted upon opposite internal faces of the casing 10, these members being each in the form of soft rubber pads adapted to clamp therebetween the outer end of the cigarette paper, as shown most clearly in Figures 7 and 8. In this modified arrangement, the coacting clamping pads 25-26 secure the lower end of the cigarette paper in such position as to maintain it in axial alignment with the tobacco filler tube 14, the upper end of the paper being held secured to the latter by the clamping pad 17 as in the previously described form of the invention. It will be noted that the use of the clamping pads 25-26 obviates the need of any intermediate support, such as the trough-shaped member 18 of Figures 2 to 5.

In both forms of the invention, the preformed tubular cigarette tamped from the compartment 11 (11' of Figure 6) by means of the plunger 16 by the simple expedient of closing the casing cover 13 (13' of Figure 6). Upon filling the paper with tobacco, the casing cover is opened and the cigarette, ready for use, is then removed from the casing.

It will be understood that the present invention is susceptible of other various changes and

modifications which may be made from time to time without involving any departure from the general principles or real spirit of the present invention, and it is accordingly intended to claim 5 the same broadly, as well as specifically, in accordance with the appended claims.

What is claimed as new and useful is:

1. In a cigarette-forming device, a hollow pocket-size casing having at one side thereof an opening adapted to provide access to the interior of the casing and at one end thereof an exteriorly disposed tobacco-receiving compartment, a tubular member extending from said compartment into the interior of said casing, said member being adapted to receive thereon in tubular extension thereof a tubular paper wrapper for a cigarette, and a closure member for said casing opening having means thereon adapted to operate conjointly with said tubular member to clamp one end of said paper wrapper upon said tubular member.

2. In a cigarette-forming device, a hollow pocket-size casing having at one side thereof an opening adapted to provide access to the interior of the casing and at one end thereof an exteriorly disposed tobacco-receiving compartment, said casing being separated from said compartment by an intervening wall, a tubular member extending from said compartment into the interior of said casing, said member being adapted to receive thereon in tubular extension thereof a tubular paper wrapper for a cigarette, a trough-shaped member secured to said casing interiorly thereof in rectilinear alignment with said tubular member adapted to receive the body portion of said paper wrapper extending from said tubular member, and a closure member for said casing opening having means thereon adapted to operate conjointly with said tubular member to clamp one end of said paper wrapper upon said tubular member and to operate conjointly with said trough-shaped member to embracingly support said extended body portion of the paper wrapper.

3. In a cigarette-forming device, a pocket-size casing having at one side thereof an opening adapted to provide access to the interior of the casing and at one end thereof an exteriorly disposed transversely extending tobacco-receiving compartment, said casing end forming the bottom wall of said compartment, a tobacco filler tube extending from said compartment from the bottom wall thereof into the interior of said casing, said filler tube being adapted to receive thereon in tubular extension thereof a tubular paper wrapper for a cigarette, a closure member for said casing opening having means thereon adapted to operate conjointly with said filler tube to clamp one end of said paper wrapper upon said filler tube, and means operative upon closure of said closure member to support the extended body portion of said cigarette paper in axial alignment with said filler tube.

4. In a cigarette-forming device, a hollow pocket-size casing having at one side thereof an opening adapted to provide access to the interior of the casing and at one end thereof an exteriorly disposed transversely extending tobacco-receiving compartment, said casing end forming the bottom wall of said compartment, a tubular member extending from said compartment from said bottom wall thereof into the interior of said casing, said member being adapted to receive thereon in tubular extension thereof a tubular paper wrapper for a cigarette, a closure member

for said casing operating having means thereon adapted to operate conjointly with said tubular member to clamp one end of said paper wrapper upon said tubular member, and means fixedly associated with said casing at the end thereof remote from said tubular member, said means being positioned for sealing the proximate end of said paper wrapper against escape of tobacco therefrom during an operation of tamping tobacco into said cigarette paper by way of said tubular member.

5. In a cigarette-forming device, a hollow pocket-size casing having at one side thereof an opening adapted to provide access to the interior of the casing and at one end thereof a tobacco-receiving compartment, a tubular member extending from said compartment into the interior of said casing, said member being adapted to receive thereon in tubular extension thereof a tubular paper wrapper for a cigarette, a trough-shaped member secured to said casing interiorly thereof in rectilinear alignment with said tubular member adapted to receive the body portion of said paper wrapper extending from said tubular member, and a closure member for said casing opening having means thereon adapted to operate conjointly with said tubular member to clamp one end of said paper wrapper upon said tubular member and to operate conjointly with said trough-shaped member to embracingly support said extended body portion of the paper wrapper, said trough-shaped member having fixedly mounted therewith at the end thereof remote from said tubular member a closure plate extending transversely across the axis of a tubular paper wrapper clampingly secured within the device.

6. In a cigarette-forming device as defined in claim 4 wherein said last-mentioned sealing means comprises a flat plate member extending transversely across the longitudinal axis of the tubular paper wrapper, said plate member being spaced from said tubular member to an extent sufficient to provide one end of the paper wrapper with an abutment engageable with said plate when the opposite end thereof is fitted upon said tubular member.

7. In a cigarette-forming device as defined in claim 4 wherein said last-mentioned sealing means comprises a pair of resilient clamping pads respectively supported upon said closure member and the opposite wall of said casing, said clamping pads being adapted upon closure of said closure member to clamp therebetween in flattened condition the outer end of said tubular paper wrapper.

GEORGE BURNSTEIN.
